ATTORNEY

UNITED STATES PATENT OFFICE.

FREDERICK A. SHATTUCK, OF NORWICH, NEW YORK.

LUBRICATING SYSTEM.

1,312,365.

Specification of Letters Patent. Patented Aug. 5, 1919.

Application filed August 11, 1917. Serial No. 185,712.

To all whom it may concern:

Be it known that I, FREDERICK A. SHATTUCK, a citizen of the United States, residing at Norwich, in the county of Chenango and State of New York, have invented certain new and useful Improvements in Lubricating Systems, of which the following is a specification.

This invention has relation to improvements in a device for automatically feeding lubricating oil to the crank case of a gasoline motor employing a splash system of lubrication.

The primary object of the invention is to provide a connection between the supply tank and the crank case of the motor wherein an air pressure will be created after a predetermined quantity of lubricating oil has been passed through the supply pipe and into the crank case.

As a further object of the invention, the device is provided with a supplementary container having connection with an auxiliary reservoir, the latter being connected to the supplementary container by an air pipe whereby an air pressure may be created in the reservoir when a certain quantity of lubricating oil is deposited in the supplementary container.

A still further object of this invention is the provision of a lubricating system which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawing, wherein is illustrated the preferred form of my invention, in which:

Figure 1 is a diagrammatic view of a portion of a crank case and the dashboard of an automobile, showing the invention applied thereto,

Fig. 2 is an enlarged vertical section through the auxiliary reservoir, and

Fig. 3 is an enlarged detail section 50 through the supplementary container.

It is well known in the lubrication of gasoline motors employing a splash system, that it is necessary to fill the crank case with a surplus quantity of lubricating oil, so that the parts to be lubricated will receive sufficient oil during the time consumed by an extended tour, and this surplus quantity is often the cause of "fouling" the spark plugs which is likely to occur until the oil has been reduced in quantity. The automatic supply of a predetermined quantity of oil to the crank case is, therefore very desirable and the present invention contemplates providing this automatic supply through the medium of vacuum-controlled means which will permit the supply tank to be disposed considerably above the crank case.

As shown by Fig. 1 of the drawing, the crank case A is disposed below the dashboard B in the usual manner. Arranged at a convenient point in front of the dashboard is a supply tank 1 provided with an inlet opening having a cap 2 for covering the opening and preventing the intake of air. The supply tank may have a capacity of two or three gallons of lubricating oil and is associated with a gage 3 mounted upon the dashboard B so that the depth within the supply tank may be determined at all times.

A supply pipe 4 is in open communication with the interior of the supply tank 1 and has a valve 5 for opening and closing the pipe. The lower terminal of the supply pipe 4 is connected to and communicates with the auxiliary reservoir 6 which comprises the cylindrical container, shown in detail in Fig. 2 of the drawing, provided at its top end with a closure 7 in screw-threaded engagement with the container for providing an air-tight joint. The supply pipe 4 extends into the interior of the reservoir 6 for a distance equal to about half the depth of the reservoir. Connected to the bottom end of the reservoir 6 is a connecting pipe which is in communication with the interior of a supplementary container 9 disposed in approximately the same plane as the bottom of the crank case A, as clearly

shown by Fig. 1 of the drawing. The supplementary container is also of cylindrical formation and its length is sufficient to receive a quantity of lubricating oil which will be of a depth equal to the depth of the oil deposited within the crank case. In other words, when the required quantity of oil is deposited in the crank case, the same level will be maintained in the supplementary container. The top of the supplementary container 9 is provided with an air vent 15 through which air is permitted to pass whereby the oil level may rise in the container 9. Connecting the supplementary container with the crank case is an outlet supply pipe 10. From the above description, it will be observed that an open passageway is established, when the valve 5 is opened, between the supply tank through the auxiliary reservoir and the supplementary container to the crank case.

An air pipe 11 has one end projected through the bottom of the auxiliary container 6 and the terminal of the pipe is disposed above the terminal of the supply pipe 2, this structure being clearly illustrated by Fig. 2 of the drawing. The lower end of the air pipe 11 is projected into the supplementary container 9 and terminates therein at a point level with the plane assumed by the quantity of oil in the crank case so that when the required quantity of oil is deposited in the crank case, the level of oil in the supplementary container will be flush with the end of the air pipe. A petcock 12 is provided in the crank case for drawing off the oil that has become polluted with carbon, or other objectionable matter.

In operation, it will be merely necessary to open the valve 5 whereupon the oil will flow from the supply tank 1 through the pipe 4, into the auxiliary reservoir 6 and through the latter and the pipe 8 into the supplementary container 9. From this container the oil passes through the pipe 10 into the crank case A. As the oil rises in the crank case, it also rises, at the same level, in the supplementary container 9. The air in the container 9 is forced upwardly as the oil rises and this air passes upwardly through the air vent 15 until the oil level has reached the end of the pipe 11. The air in the pipe 11, therefore, prevents the oil from rising into the pipe 11 but since there is a direct connection between the oil in the supplementary container 9 and the auxiliary reservoir 6 by the pipe 8, it will be obvious that the latter pipe will be filled with oil and since the valve 5 is still open, the flow of oil into the auxiliary reservoir will continue until the oil reaches the low end of the pipe 4 as shown to advantage in Fig. 2 of the drawing. An air pressure is created in the space

indicated at 18 in Fig. 2 and consequently the oil is not permitted to rise any higher than and will maintain this level until some of the oil in the crank case has been used.

From the foregoing, it will be observed that a very simple and durable lubricating system has been provided, the details of which embody the preferred form. I desire it to be understood, however, that slight changes in the minor details of construction may be made without departing from the spirit of the invention or the scope of the claims hereunto appended.

I claim:

1. In combination with a supply pipe and an outlet pipe disposed below the plane of the said tank, means for forming a communication passage between the tank and the said pipe, an auxiliary reservoir intermediate the connections of the said means with the pipe and the tank, and means for creating an air pressure within the auxiliary reservoir when a certain quantity of the contents of the tank has been ejected through the said pipe.

2. In combination with a supply tank and an outlet pipe, a supplementary container so connected to the said outlet pipe, connecting pipes in open communication with the said tank and the supplementary container, and an air pipe cooperating with the said supplementary container for forming an air pressure when a certain quantity of the contents of the tank has been ejected through the said pipe.

3. In combination with a supply tank and an outlet pipe disposed below the plane of the said tank, a supplementary container connected to the outlet pipe, an auxiliary reservoir in communication with the said tank and disposed below the same, and a connecting pipe and an air pipe both in open communication with the auxiliary reservoir and the said supplementary container, the said air pipe being projected into the said auxiliary container to a point adjacent the top thereof.

4. In combination with a supply tank and the crank case of an automobile, a supplementary container in open communication with the interior of the crank case, an auxiliary container connected to the said supply tank and the said supplementary container, and means for forming an air pressure in the said auxiliary reservoir when a quantity of the contents of the tank has been deposited in the crank case.

5. In combination with a supply tank and the crank case of an automobile motor, a supplementary container in open communication with the crank case and adapted to receive a quantity of the contents of the tank equal in depth to the quantity disposed in the

crank case, an auxiliary reservoir, and means connecting the reservoir and the tank with the said supplementary container including an air pipe adapted to create an air pressure within the said auxiliary reservoir when a predetermined depth has been provided in the supplementary container.

In testimony whereof I affix my signature in presence of two witnesses.

FREDERICK A. SHATTUCK.
